UNITED STATES PATENT OFFICE.

HARRY COULSTON, OF PHILADELPHIA, PENNSYLVANIA, ASSIGNOR TO THE PHILADELPHIA TEXTILE MACHINERY COMPANY, OF PHILADELPHIA, PENNSYLVANIA, A CORPORATION OF PENNSYLVANIA.

PROCESS OF REMOVING STOCKINGS FROM STOCKING-BOARDS.

1,141,777.

Specification of Letters Patent.

Patented June 1, 1915.

Application filed February 26, 1913. Serial No. 750,873.

To all whom it may concern:

Be it known that I, HARRY COULSTON, a citizen of the United States, residing in Philadelphia, Pennsylvania, have invented 5 certain Improvements in the Process of Removing Stockings from Stocking-Boards, of which the following is a specification.

This invention relates to certain improvements in the process of removing stockings 10 from stocking boards, particularly during the manufacture of the stockings.

The object of the invention is to remove the stocking from the board in such a manner that it will not be torn or unduly 15 stretched and will be properly pressed, so that one stocking after another can be laid on a pile with the foot in proper relation to the leg.

In carrying out this idea the board can 20 either be removed from the stocking while the stocking is being held, or the stocking can be removed from the board while it is being held, or both can be moved in unison in opposite directions if desired.

25 The accompanying drawings illustrate in diagram the different steps of the process.

Figure 1, is a plan view showing a stocking mounted on the board in such position that it can be grasped at the toe and at the 30 heel; Fig. 2, is a view showing mechanism grasping a stocking at the toe and heel, with the board in place prior to being removed; Fig. 3, illustrates the first step of the process of removing a stocking from a stocking 35 board; Fig. 4, illustrates the step where the board has been removed from the foot portion and is passing through the angle portion; Fig. 5, is a view illustrating the stocking board emerging from the leg portion of 40 the stocking; and Fig. 6, is a side view of a stocking mounted on a stocking board and in the position illustrated in Fig. 2.

Prior to this invention no special process 45 was used in the removal of a stocking from a stocking board. No mechanism was employed and the removal was accomplished by an operator merely grasping the heel of a stocking and jerking the board out of the stocking. Applicant has found that better 50 results are obtained than heretofore by a careful removal of a stocking from the stocking board.

The mechanism shown for carrying out this process will be fully set forth and

claimed in an application for patent which 55 will be filed at a later date.

Stockings are dampened and then dried by heat and the usual practice is to mount these stocking boards in a drying chamber through which hot air circulates, although recent developments have produced continuous machines for feeding stocking boards with stockings thereon through drying chambers, and as a stocking emerges from the drying chamber it is removed from the 60 board. Stockings may also be dried by being placed on hollow forms in which air or steam is allowed to circulate, or they may be dried by means of an electric current from a heater surrounding the stocking, or from 65 the coils in the board or form.

In the present instance, I have illustrated simply the ordinary stocking board, which 70 is of thin metal or wood, and over which a stocking is placed prior to the drying operation.

Referring to the drawings, 1 is the stocking.

2 is the board or form over which the 75 stocking is placed.

3 and 4 are gripping jaws, in the present instance forming part of a mechanism illustrated in Figs. 2 and 6. Each jaw has a bottom plate 5 and a clamp 6. The jaws are mounted on the arms 7, and the jaw 3 80 is located on a carrier 8 to which a counter-balance 10 is attached by a cord 9.

In Fig. 1, the clamps 6 are moved out of the path so as to allow a stocking board, with the stocking thereon, to position itself directly over the bottom plates 5 of the gripping jaws 3 and 4. After a stocking board is in position the clamps are moved over the top of the stocking, clamping it to the bottom plates 5. The gripping jaw 4 85 grasps the heel of the stocking and the gripping jaw 3 grips the toe of the stocking, as illustrated in Fig. 2. Longitudinal movement in the line of the arrow *a*, Fig. 2, is imparted to the board 2 and the removal of the board from the foot of the stocking causes the gripping jaw 3 to move toward the gripping jaw 4, overcoming the counter-weight 10, as clearly shown in Fig. 3. This 90 brings the toe and heel portions nearer together than in Fig. 2, and allows the heel portion of the stocking to be withdrawn from the board to a greater extent than the 95 100 105

toe portion, this releases the heel of the board so that, as the movement of the board is continued, the foot 11 of the board will pass through the angle portion 12 of the 5 stocking at such an angle as to give the ankle the least amount of stretch possible.

The direction of movement of the board is at an angle to the longitudinal line through the leg and as the foot of a stocking board leaves the ankle portion of the stocking, as illustrated in Fig. 4, it presses 10 out the leg portion as it moves to the position illustrated in Fig. 5, the toe and heel acting as spreaders for the leg portion, so 15 that one stocking after another is placed in a pile until the number desired is reached.

As the board is being removed from the stocking the toe gripping jaw 3 is moved 20 from the heel jaw 4, due to the counter-weight 10 in the present instance, and it is turned in the direction of the arrow *b*, Fig. 3, until it assumes the position illustrated in Fig. 4, the jaw 4 turning with it, as the leg has assumed a position with its longitudinal line parallel with the arrow *a*, indicating 25 the movement of the board, Figs. 4 and 5, so that when the stocking is released from the jaws 3 and 4 the foot portion is in the same relation to the leg as it was when on 30 the board and all creasing or unevenness is avoided.

While I have shown mechanism for carrying out this process, it will readily be understood that the operation can be done by 35 hand, as well as by the mechanism shown.

I claim:—

1. The process herein described of removing stockings from flat boards or forms in a

flat unrumpled condition, said process consisting in grasping the heel and toe of the 40 stocking and engaging the board or form, moving one part with respect to the other and withdrawing the heel portion of the stocking in advance of the toe so as to allow the heel of the board to pass the portion back 45 of the heel of the stocking without undue stretching and then continuing the movement so that the foot portion of the board will act as a spreader for the leg of the stocking. 50

2. The process herein described of removing stockings from flat boards or forms in a flat unrumpled condition, said process consisting in grasping the stocking at the heel and at the toe, moving the heel toward the toe so that it will be removed in advance of the toe to allow the heel of the board to pass the portion back of the heel of the stocking without undue stretching and continuing the movement on a line which will cause the 55 foot portion of the board to act as a spreader for the leg portion of the stocking, then turning the foot of the stocking so that when the board is removed from the stocking the foot thereof will have the same 60 relation to the leg as it had prior to the removal, the stocking being flat and unrumpled and properly spread throughout its 65 entire length.

In testimony whereof, I have signed my 70 name to this specification, in the presence of two subscribing witnesses.

HARRY COULSTON.
